UNITED STATES PATENT OFFICE.

HOWARD A. THOMPSON, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed February 6, 1924. Serial No. 690,929.

My invention relates to railway traffic controlling apparatus comprising train carried governing means controlled by energy received from the trackway. More particularly my invention relates to the trackway portion of such apparatus.

I will describe one form of trackway apparatus embodying my invention, and will then point out the novel features thereof in 10 claims.

The accompanying drawing is a diagrammatic view showing one form of trackway apparatus embodying my invention.

Referring to this drawing, the reference 15 characters 1 and 1^a designate the track rails of a stretch of railway track over which traffic normally moves in the direction indicated by the arrow. These track rails are divided, by means of insulated joints 2, into 20 a plurality of successive track sections of which only one section A—D, is shown in the drawing.

Section A—D is provided with a track relay R having two windings 7 and 9. This 25 relay is so arranged that it will be energized only when windings 7 and 9 are supplied simultaneously with alternating currents of the same frequency but differing in phase. Winding 9 is constantly supplied with alternating current from some suitable source, such as an alternator G, over line wires 3 and 3^a. The relay R is so constructed that winding 9 has considerable reactance and the current through winding 9 therefore lags 30 behind the electromotive force of generator G. The other winding 7 of relay R is constantly connected with the rails 1 and 1^a adjacent the exit end of section A—D. This winding 7 has a high impedance, and for 35 purposes which will appear hereinafter, a resistance 8 is interposed between one rail, 1, of the section, and winding 7 of relay R.

Located at the entrance end of section A—D is a track transformer T having its 40 primary winding 5 constantly supplied with alternating current from line wires 3 and 3^a. The secondary 4 of transformer T is constantly connected with the rails adjacent the entrance end of section A—D 45 through a resistance 6. It follows that when section A—D is unoccupied, alternating current flows from secondary 4 of transformer T, through resistance 6, the rails 1 and 1^a of section A—D, resistance 8 and winding 7

of relay R in series. Due to the effect of resistances 6 and 8, this current is more nearly in phase with the electromotive force of generator G than is the current through winding 9. Under these conditions therefore the currents in windings 7 and 9 of relay R are displaced in phase and relay R is energized. The relay R may be used to control trackway signaling means or other traffic governing means in any desired manner, and the current supplied to the section by 65 transformer T, I will term "signaling current".

Means are also provided for supplying the section with other current for controlling the train carried governing means and this 70 current I shall designate, for purposes of convenience, "train governing current". For supplying the train governing current to the section I provide a transformer U' having its secondary 11 connected with the rails 75 adjacent the exit end D of the section. Interposed between the secondary 11 of transformer U' and one rail 1 of the section is a reactive impedance or reactor 10.

The supply of energy to the primary 12 of 80 transformer U' is controlled by traffic conditions in advance of section A—D. For example, as shown in the drawing, this control is effected by means of a circuit controller 13 operated by a signal S associated 85 with the section to the right of section A—D and located at point D. This signal may be of any form and may be controlled in any suitable manner. Circuit controller 13 is closed only when signal S indicates "pro- 90 ceed" or "caution". Primary 12 of transformer U' is supplied with alternating current from line wires 3 and 3^a over circuit controller 13. It therefore follows that train governing current is supplied to section 95 A—D by transformer U' only when signal S indicates caution or proceed.

The reactor 10 is so proportioned that the current flowing from the secondary 11 of transformer U' through winding 7 of relay 100 R is substantially in phase with the current in winding 9 of relay R, and therefore relay R can not be energized by train governing current from transformer U'. Further protection may be secured by adjusting the 105 parts so that the electromotive force supplied by the transformer U' is less than the electromotive force required to be applied

across relay winding 7 and resistance 8 to cause a sufficiently large current to flow through winding 7 to energize relay R.

It should be pointed out that the track-way apparatus herein shown and described is suitable for co-operation with train carried governing means in such manner that when the train occupies a stretch of track which is supplied with alternating current, a proceed indication is received aboard the train and when the train occupies a stretch of track to which no such current is supplied, a stop indication is received aboard the train. In at least one form of train carried apparatus arranged to operate in this manner the train-carried governing mechanism is controlled by the trackway current through the medium of receiving apparatus placed in inductive relation with the track rails in advance of the forward axle of the train. With such apparatus it is obvious that the source of train governing current must always be connected with the rails in advance of the train as otherwise the train governing current would be shunted away from the receiving apparatus by the wheels and axles of the train.

As shown in the drawing signal S is at proceed, and therefore transformer U' is energized. Transformer T is also energized and relay R is therefore picked up.

I will now assume that a train moving in the direction of the arrow enters section A—D. As the train passes point A, signaling current supplied by transformer T is shunted away from winding 7 of relay R. I have already explained that train governing current from transformer U' cannot pick up relay R and this relay therefore becomes deenergized.

As the train proceeds through the section it is constantly supplied with train governing current from transformer U', and the train therefore receives a proceed indication throughout the section.

I will now assume that signal S indicates stop, as when the section to the right of point D is occupied by a train. The supply of energy to the primary of transformer U' is therefore discontinued. If now a train proceeds through section A—D, the train will receive a stop indication throughout the section due to the absence of train governing current.

Although I have herein shown and described only one form of trackway apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a stretch of railway track, a

track relay having two windings and arranged to be energized only when the currents in said two windings are displaced in phase and one said winding being connected with said stretch, means for constantly supplying the remaining winding of said relay with an alternating current, means for supplying said stretch with a second alternating current displaced in phase with respect to said first current, and means responsive to traffic conditions for at times supplying said stretch with an alternating current substantially in phase with said first current. 70

2. In combination, a stretch of railway track along which traffic moves in only one direction, said stretch being provided with insulated joints forming an electrically isolated section, a source of alternating track circuit current connected across the rails adjacent the entrance end of said section, means controlled by traffic conditions in advance of said section for connecting a second source of alternating current across the rails adjacent the exit end of said section, and a track relay connected across the rails adjacent the exit end of said section and responsive to said track circuit current but not to current from said second source. 80

3. In combination, a stretch of railway track along which traffic moves in only one direction, said stretch being provided with insulated joints forming an electrically isolated section, a source of alternating track circuit current connected across the rails adjacent the entrance end of said section, a signal located at the exit end of said section for governing traffic in advance of the section, means controlled by said signal for connecting a second source of alternating current across the rails adjacent the exit end of said section, and a track relay connected across the rails adjacent the exit end of said section and responsive to said track circuit current but not to current from said second source. 95

4. Railway traffic controlling apparatus comprising a stretch of railway track, a source of alternating current connected adjacent one end of said stretch, a second source of alternating current, means responsive to traffic conditions for at times supplying current from said second source to the other end of the stretch, and a track relay connected with said stretch adjacent said second source and responsive to current from one only of said sources. 100

5. Railway traffic controlling apparatus comprising a stretch of railway track, a source of alternating current connected adjacent one end of said stretch, a second source of alternating current, means responsive to traffic conditions for at times supplying current from said second source to the other end of said stretch, and a track relay connected with said stretch adjacent said second source and responsive to current from one only of said sources. 115

second source and responsive to current from said first source but not to current from said second source.

6. In combination, a stretch of railway track provided with insulated joints forming an electrically isolated section, a source of alternating track circuit current connected across the rails adjacent one end of said section, a signal located adjacent the other end of said section for governing traffic out of the section, means controlled by said signal for connecting a second source of alternating current across the rails adjacent the second end of said section, and a track relay connected across the rails adjacent the second end of said section and responsive to said track circuit current but not to current from said second source.

7. Railway traffic controlling apparatus comprising a stretch of railway track, a track relay having two windings and ar-

ranged to be energized when said windings are supplied with alternating currents of the same frequency but displaced in phase, means for constantly supplying one said winding with a first alternating current, means for constantly connecting the remaining said winding with the stretch, a first source of alternating current connected with the stretch, means interposed between said source and said stretch for causing the current from said source to be displaced in phase from said first current, a second source of alternating current connected with the stretch, and means interposed between said second source and said stretch for causing the current from said second source to be substantially in phase with said first current. 30 35

In testimony whereof I affix my signature.

HOWARD A. THOMPSON.
